UNITED STATES PATENT OFFICE.

ANTHONY M. BASMAN, OF DETROIT, MICHIGAN.

ROTATABLE VENTILATOR-HOOD.

1,295,953.

Specification of Letters Patent.

Patented Mar. 4, 1919.

Application filed August 15, 1918. Serial No. 249,946.

To all whom it may concern:

Be it known that I, ANTHONY M. BASMAN, a citizen of the United States, and residing at Detroit, in the county of Wayne and State 5 of Michigan, have invented a new and Improved Rotatable Ventilator-Hood, of which the following is a specification.

This invention relates to rotatable hoods adapted to be mounted on the upper ends of 10 ventilator flues or pipes, and its object is to so construct a hood that wind blowing against it will pass up inside of the hood and then down and out through a discharge opening in the side away from the wind. It 15 further consists in a ventilator hood which will be strong and rigid in construction, and in which the various parts are so positioned that air currents passing into said hood through proper openings from the outside 20 will have an aspirating effect upon the air or gases within the ventilating flue or pipe upon which the hood is mounted.

This invention consists, in combination 25 with a thimble constituting a part of the ventilating flue or pipe, of a rotatable member comprising an outer upwardly tapering shell having a discharge opening and a vane to hold this opening away from the wind. It further consists in a deflector of cylind- 30 rical shape within the shell to compel the air currents from the outside to ascend within the shell and then permit them to pass out through the discharge opening in the shell together with the air and gases 35 ascending in the ventilator pipe.

In the accompanying drawings, Figure 1 is a side elevation of this improved ventilator. Fig. 2 is a view of the same, partly in bottom plan and partly horizontal sec- 40 tion on the line 1—1 of Fig. 1. Fig. 3 is a central vertical section on the line 3—3 of Fig. 2. Fig. 4 is a plan of the ventilator.

Similar reference characters refer to like parts throughout the several views.

45 While this rotatable hood may be mounted directly on the upper ends of ventilator pipes or flues, I prefer to provide a cylind- 50 rical thimble 1 which will fit such pipes or flues. On this thimble, the hood will be 55 rotatably mounted in any desired manner but for hoods of moderate dimensions I prefer to secure an upright rod or shaft 2 in position within the thimble by means of the braces 3 and 4, each preferably provided

The hood is made up of a cap 5, a vane 6 secured to the top of the cap, a shell 7 and a cylindrical deflector 8. The cap 5 is substantially conical with a flattened portion under the vane and in the center on the inside is secured the socket 9 to receive the bearing balls 10, the recess for the balls being deep enough to receive the upper end of the rod 2 and thereby properly position the hood. Extending down from this socket 60 are the straps 12 (preferably three) which are connected at their lower ends to the deflector 8. One side of the hood (the left in the drawings) will always be toward the wind and the opposite side and discharge 65 opening will always be away from the wind. In this description and claims the former will be termed the windward and the latter the leeward side of the hood.

The lower end of this deflector is a complete cylinder 13 and is only slightly larger than the upper end of the thimble 1 around which it turns freely and by which it is centered. This deflector extends up into the shell and is connected to the lower part of 80 the shell by the vanes 14, 15, 16 and 17 which are parallel to the line 3—3 of Fig. 2 near that line but deflect therefrom as they near the flattened portions 18 of the shell. The shell is spaced away at the bottom 85 around the deflector 8 between the edges of the horizontal plate 19 which edges are parallel and tangential to the deflector 8. The vertical leeward edges 20 of the sheet constituting the hood are also parallel to 90 each other and to the edges of this plate 19 to which they are attached. Inclined slats 22 may extend between the edges 20 across the discharge opening 25 of this ventilator hood, but these slats may be omitted if de- 95 sired, their office being only to stiffen the structure and to shed rain when the hood is in the open air.

The cap 5 is formed with a substantially flat lip 24 which extends across the top of 100 the discharge opening 25. It will be noticed that the vane 6 is central with the discharge opening. The deflector 8 is not a complete cylinder but the distance across between the bottom of its upright edges 26 is substan- 105 tially the width of the discharge opening 25. The bottoms of these vertical edges 26 are preferably bent out parallel to each other and attach to the parallel edges of the plate 19. This plate is formed with a flange 21 110

that extends down into the cylindrical band 13 to which it is secured. The action of this hood is as follows.

The vane 6 will hold the opening 25 leeward of the wind so as to take advantage of what aspirating effect there may be. As the shell 7 of the hood tapers upwardly, the spaces between the shell 7, the deflector 8 and the vanes 14 to 17 will taper upwardly. The positions of these vanes are such and the spaces between them taper in such a manner that comparatively strong jets of air will rise around one half the circumference of the deflector and these jets will together have a siphoning action on the gases in the thimble 1. These jets will strike against the cap 5 and be deflected toward the only portion where there are no jets, that is, toward the opening 25. In addition, the air or wind 20 which is caught between the lower portions of the flat sides 18 of the shell and the vanes 17 will also pass up into the hood and at once pass out laterally through the opening 25, producing an aspirating effect on the gases 25 and air within the deflector and the thimble 1.

The proportions and sizes of the various parts may all be changed by those skilled in the art without departing from the scope of 30 my invention as defined by the following claims.

I claim:—

1. A rotatable ventilator hood comprising an upwardly tapering shell having a side 35 opening and a vane attached to the top of the shell and extending centrally of the opening, a cylindrical deflector extending up within the shell and of less diameter than the shell, and vanes between that portion of the shell 40 which is opposite the side opening therein and the deflector and constituting upwardly tapering air passages, said deflector termi-

nating in line with said side opening in the shell, and means to rotatably support said hood.

2. A rotatable ventilator hood comprising a shell having a side opening and means whereby wind may turn the shell so that said opening will be on the leeward side thereof, a semi-cylindrical deflector extending up into said shell and having a portion of its edges extending substantially uprightly and connecting to the hood at the edges of said opening, a cap for the shell, upright vanes between the shell and deflector, and means to rotatably support the hood.

3. A rotatable ventilator hood comprising an upwardly tapering shell having a side opening, a substantially conical cap for the 60 shell and a vane on the cap to hold said opening to leeward, a deflector extending up into the shell and having that portion below the shell in the form of a cylinder and terminating in line with the sides of said opening in 65 the shell, and vanes between the windward portions of the shell and deflector to form upwardly tapering air passages extending to the top of said deflector on the windward side thereof.

4. A rotatable ventilator hood comprising an upwardly tapering shell having a rectangular side opening, the edges of the shell adjacent the opening extending upwardly, a cap for the shell having that portion adjacent the opening extending horizontally, a cylindrical deflector extending up into the shell and terminating substantially at the middle of the height of said opening, and vanes between the portions of the shell and deflector opposite said opening to form tapering air passages.

ANTHONY M. BASMAN.
